CLAIM

The ornamental design for a heated hair brush, substantially as shown and described.

DESCRIPTION

FIG. 1 is a perspective view of a heated hair brush showing my new design, it being understood that the teeth are continuous over the span indicated by dot-dash line and the conventional power cord is broken away for ease of illustration.

FIG. 2 is a front elevational view thereof;

FIG. 3 is a rear elevational view thereof;

FIG. 4 is a top plan view thereof;

FIG. 5 is a left side elevational view; the right side is a mirror image thereof;

FIG. 6 is a bottom plan view thereof.

Fig. 2.
